E. O. HICKS.
AUTOMATIC RAILWAY CURVE LUBRICATOR.
APPLICATION FILED MAR. 6, 1908.

UNITED STATES PATENT OFFICE.

ENOCH OGDEN HICKS, OF ST. JOSEPH, MISSOURI.

AUTOMATIC RAILWAY-CURVE LUBRICATOR.

No. 905,531.

Specification of Letters Patent.

Patented Dec. 1, 1908.

Application filed March 6, 1908. Serial No. 419,601.

To all whom it may concern:

Be it known that I, ENOCH OGDEN HICKS, a citizen of the United States, residing at St. Joseph, in the county of Buchanan and State of Missouri, have invented certain new and useful Improvements in Automatic Railway-Curve Lubricators; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

The object sought by me in this invention is to provide a device by which curves of electric or other street car railways may be automatically lubricated at the passage of every car carrying a lubricator, thereby keeping the curves at all times thoroughly lubricated, and materially reducing the expense incurred in having the curves lubricated.

I attain my object by the mechanism illustrated in the accompanying drawings, in which:—

Figure 1 is a perspective of a car floor and side, broken away, a car wheel and brake beam, a bracket supported on said beam, a lubricator carried thereby, a connecting spiral spring thereon and a lubricating swab in engagement with the flange of said wheel; Fig. 2 is a perspective of a tank adapted to carry a supply of the lubricant; Fig. 3 is an enlarged view of the lubricator and the holder which is adapted to carry the swab which lubricates the flange of the wheel, and Fig. 4 is a top view of the swab by which the lubricant is applied to the flange of the wheel.

Similar letters refer to similar parts in the several views.

In the drawings A is a bracket shown supported on a brake beam A'. I preferably support the bracket in this manner, but any suitable means of support may be used.

B is the body of the lubricator. C is a swab carried in a holder D, which holder is preferably cast as a part of said lubricator; said holder stands at an angle that will enable it to automatically carry said swab into contact with flange h of wheel H. L is an axle for said wheel. D' is a steel plate which is fastened at its upper edge to said holder, its side and bottom edges left free as

shown in Fig. 3. Swab C is preferably made of woolen felt material and is provided with perforations d d through which screws d' d' are inserted, thereby assisting in holding it in place in said holder. By tightening screws d' d' the lower portion of plate D' is pressed downward, thereby increasing the tension on swab C; the spread of the swab caused by this tension checks the exudation of an undue quantity of the lubricant.

J is the foot of bracket A and serves as a means of attaching the bracket to the brake beam or any suitable support.

G is an axle screwed into or rigidly fastened to the side of the lubricator and G', on the opposite side, is a tube screwed into said lubricator having an upwardly turned end F, said tube thus serving both as an axle and supply pipe. As shown by dotted lines this tube may be connected by hose with nipple i on a tank I. But such tank may be dispensed with and any other suitable means for obtaining a supply of lubricant adopted without changing the purpose of my invention.

E is a spiral spring one end being connected with the top of the body of the lubricator, the other end adapted to connect with the floor K of a car or other rigidly set support.

When the truck of a car is running on a straight track, the lubricator and swab holder will be in normal position, as shown by dotted lines in Fig. 1; when a car reaches a curve and the truck of the car is swung out of its normal position, said spring is thereby automatically elongated and the lubricator and holder tipped to the position shown in Fig. 1, and the swab is brought in contact with the inside of the flange of the wheel. The swab thus pressed against the flange of the wheel will be exuding the lubricant on said flange as the wheel revolves until the wheel again reaches a straight track. The flange of the wheel during the passage around the curve has been conveying the lubricant received from the swab to the curve of the rail. This automatic movement will be repeated at every curve.

What I claim and desire to secure by Letters Patent, is:—

1. In an automatic railway curve lubricator the combination with a car wheel, a brake beam and the floor of a car, and a supply tank, of a bracket rigidly fastened on said beam, a lubricator, a solid axle on said

lubricator, a tube opposite thereto serving both as an axle and a supply pipe, a spiral spring having connection at one end with said lubricator, the other end adapted to connect with said floor, an outwardly turned holder at the bottom of the lubricator, an adjustable plate on the front of said holder, a swab provided with perforations in said holder and screws adapted to engage with 5 said perforations to retain said swab in position and regulate the pressure of the plate on the swab, substantially as set forth and shown.

2. In an automatic railway curve lubricator the combination with a car, of a rigidly supported bracket, a lubricator provided with axles carried in said bracket, a holder at the bottom of said lubricator, an adjustable plate thereon, a lubricating swab 10 carried by said holder, a spiral spring form-

ing connection between the car floor and the lubricator to automatically tip said lubricator and hold said swab in contact with the flange of a wheel while on a curve, substantially as shown and described. 25

3. In an automatic railway curve lubricator the combination with the body of the lubricator, of a swab holder at the base thereof its top, sides and back integral therewith, a plate attached to the front thereof and means for adjusting said plate to hold a swab and regulate the exudation of the lubricant from the body of the lubricator, substantially as described and set forth.

In testimony whereof, I affix my signature 30 in presence of two witnesses.

ENOCH OGDEN HICKS.
